Inventor,
William T. Rose, by
G. Kennedy,
Attorney.

UNITED STATES PATENT OFFICE.

WILLIAM T. ROSE, OF WATERLOO, IOWA.

POWER-ACTUATED SAFETY-RAZOR.

1,374,608.

Specification of Letters Patent. Patented Apr. 12, 1921.

Application filed June 19, 1919. Serial No. 305,305.

To all whom it may concern:

Be it known that I, WILLIAM T. ROSE, a citizen of the United States of America, and a resident of Waterloo, Blackhawk county, 5 Iowa, have invented certain new and useful Improvements in Power-Actuated Safety-Razors, of which the following is a specification.

My invention relates to improvements in 10 power actuated safety razors, and the object of my improvement is to provide means for reciprocating the blade of a safety razor, which means shall be simple, light, inexpensive, noiseless and convenient for manipulation in use, as also easy to assemble or disassemble.

This object I have accomplished by the means which are hereinafter described and claimed, and which are illustrated in the 20 accompanying drawings, in which Figure 1 is a medial longitudinal section of my improved device; Fig. 2 represents the different parts or elements of my improved device as disassembled from each other and 25 placed in their order of succession, with the elements shown in perspective; Fig. 3 is a plan of said device as assembled; Fig. 4 is an elevation of the blade holding means, and Fig. 5 is an elevation of the blade, 30 while Fig. 6 is a cross-section of the hollow shank of the device, taken at the location of the annular spring 10 thereon.

Similar numerals of reference denote corresponding parts throughout the several 35 views.

The rectangular blade 1 of my device is of the so-called "wafer" type and has rectangular slots 2 along its medial longitudinal line, and also has on the same line and 40 positioned between said slots, small circular orifices to receive screws 3 which secure it removably to a block 4, the latter being shown in said Figs. 1 and 2. The block 4 is rectangular in plan and has a medial vertical elongated socket 5 for a purpose to be 45 described. The numeral 10 denotes the backing-plate for the blade 1 and is of similar rectangular form, of slightly greater length, and provided on its opposite longitudinal edges with small detents projecting beyond the cutting edges of the blade. This 50 backing-plate has an integral rearward extension or boxing 11, rectangular internally, with its hollow 12 longer than the 55 said block 4 but of like vertical height to

permit said block reciprocatory scope of movement when mounted therein with the blade 1 in contact with the front face of the backing plate.

The numeral 6 denotes a face or guard-plate 60 preferably channeled as shown in Fig. 2, with its longitudinal edge parts sloped oppositely at a side angle. This guard-plate is of the same length as the backing-plate 10, but is slightly narrower in width 65 than the blade 1 upon which it is mounted. This arrangement of the parts is best shown in Fig. 4. The guard-plate 6 has small orifices along its medial longitudinal line to receive the screws 8 which serve to 70 secure it to the backing plate 10 after being pressed through the slots 2 in the blade 1. Elliptical plate springs 7 are mounted between the heads of said screws 8 and the abutting face of said guard-plate to bear 75 resiliently at their opposite ends thereagainst. The springs are provided with elongated longitudinally-disposed slots 9, and the heads of the screws 8 are excised on opposite sides to adapt them for passage 80 through the slots 9, and they may be then turned across said slots, as shown in Fig. 4, to mount the springs removably.

The boxing 11 and the contained reciprocatory block 4 may be otherwise formed, 85 but are shown as being diminished in thickness downwardly in order to mount the hollow cylindrical shank 15 of the device thereon at a convenient angle for use relative to the position of the blade 1. Said shank 15 90 has a rectangular outwardly directed beveled flange 13 which may be removably fastened in registration upon the rear face of the boxing 11 by means of screws 14. A rotatable cylindrical element or shaft 21 95 is mounted within the shank 15 coaxially, being of somewhat less interior diameter, but rotatable within inner annular bearing flanges 19 and 20 of said shank to keep it 100 properly centered, and it has an outwardly directed annular flange 25 abutting upon the rear face of the flange 20 to limit its forward movement. The forward end 31 of the shaft 21 which projects beyond said flange 19 is diminished and threaded to receive a removable head 22 of cylindric form 105 which fits the interior bore of said shank.

An eccentric crank-pin 23 is fixed on the forward face of the head 22 and upon said pin in loosely mounted an anti-friction 110

sleeve 24. Said pin and sleeve extend operatively into the slot 5 in said block 4.

- The numeral 30 denotes a flexible power-shaft formed of helical spring wire and rotated by a power-plant not shown. A cylindric head 29 is fixed on the free extremity of the flexible shaft 30 and has a diminished extremity seated removably in a hollow, coaxially, of the rear end of the shaft-part 21.
- 10 The part 21 and its flange 25 are longitudinally slotted at 26 on one side to receive a feather or spline 27 on the head 29 to permit the latter to rotate the former. The shank 15 has an annular groove 16 in which 15 is seated the annular spring 17, the latter being in the form of a split-ring, with one end 32 bent inwardly to pass through an orifice 18 in the shank, entering and engaging an annular groove 28 in the head 29.
- 20 By this means, said flexible shaft is releasably connected to said shaft-part 21.

When the flexible shaft 30 and the associated shaft-part 21 are rotated, the crank-pin 23 with its sleeve 24 moves rotatably and slidably within the socket 5 to rapidly reciprocate the block 4 and razor-blade 1. The user can conveniently employ the device in the shaving operation, shifting it as desired, and attention is especially called to the fact that 25 the double-edged blade, with its guards, may have either cutting edge employed without the necessity for rocking the device as a whole, it only being necessary to slightly tilt 30

the device to bring either edge into operation.

35

As the moving parts are so few and are mounted frictionlessly, the device is noiseless and free from shock.

Various modifications may be made in this device without departing from the scope of 40 the invention.

Having described my invention, what I claim as new and desire to secure by Letters Patent, is:

In a device of the character described, 45 a double-edged blade, a holder therefor comprising bodies between which the blade is removably mounted for limited reciprocation with both cutting edges exposed, one body having a hollow shank with a widened head 50 provided with a rectangular hollow bearing, said blade having a vertically slotted rectangular shank removably mounted thereon and mounted to reciprocate in and being of less length than the widened hollow of said 55 head, a shaft mounted rotatably and removably in said hollow shank and having a removable head provided with a crank-pin, the latter seated movably in the slot in the blade-shank, and a flexible rotatable operating shaft detachably connected to said first-mentioned shaft and adapted to be rotated by power-driven means.

Signed at Waterloo, Iowa, this 31st day of May, 1919.

WILLIAM T. ROSE.
